UNITED STATES PATENT OFFICE.

FREDERICK WILLIAM NUNN, OF MELBOURNE, VICTORIA, AUSTRALIA, ASSIGNOR TO
NUNNDAY PROPRIETARY LIMITED, OF MELBOURNE, AUSTRALIA, A CORPORATION
OF VICTORIA.

CASTING OF DENTURES IN METAL.

Application filed July 30, 1926, Serial No. 126,066, and in Great Britain August 19, 1925.

This invention relates to improvements in apparatus for casting dental plates made of gold or other metals and in particular to apparatus of the type wherein metal is melted on an investment containing the mould and carried in a pot or crucible, the investment being swung round on the end of a rod capable of being rotated in the machine. The molten metal in the crucible is caused by centrifugal force to pass through sprue holes therein into the mould to form the denture.

It is an object of this invention to ensure that the molten metal shall pass through the sprue holes into the mould by gravity and centrifugal force in such a manner that the metal shall be steadily and effectively deposited therein in very close contact with the surface of the mould.

20 To this end the invention is directed to providing apparatus which, during the time that the pot or crucible is being swung on the rod, will permit of lateral oscillating movements being imparted to the crucible.

25 It is also an object of the invention to dispense with the counterweight usually applied in connection with a rotating weight upon a rod; to provide the crucible with very small exit holes for the discharge of the molten metal, and to keep the investment containing the mould at a temperature, up to the moment of casting, close to the melting point of the metal.

30 The pot or crucible that it is proposed to use in this machine is according to that described in United States specification forming part of Letters Patent No. 1,534,952.

35 But in order to fully understand the invention reference is made to the accompanying drawings, in which,

Fig. 1 is a perspective view of the apparatus.

40 Fig. 2 shows the gear box in side elevation with turning handle and attachment 45 to prevent the handle being moved the wrong way.

Fig. 3 is a perspective view of the said attachment and

45 Fig. 4 is a like view of a crucible with sprues attached over a wax pattern of the proposed denture.

The swinging machine is set up on a base-plate 5, the pedestal 6 of same being secured to the plate. On the pedestal is a

55 gear box 7 containing geared wheels and a handle 8 for rotating same. The wheels are geared to rotate the driven member about five (5) times faster than the driving wheel and on the driven wheel spindle 9, that projects laterally from the gear box, the investment basket or stirrup 10 is hung. This spindle 9 is made to a loose fit in its bearing and no counterweight is provided to the basket 10. The base plate 5 is supported by bolts 11 on a plate 12 and is cushioned on 60 springs 13 on the bolts.

65 The investment containing the wax pattern 16 is held in the basket and heat is applied to reduce the pattern and form the mould. At the same time metal from which 70 the denture is to be made is placed in the crucible 19 on the investment and which is in communication with the mould through, preferably, three sprue holes and the connections. This metal is reduced by heat to a 75 molten condition and the handle is then turned to rotate the basket about the spindle 9. When this occurs a centrifugal force is set up that tends to transfer the metal from the crucible through the sprues to the heated mould, but at the same time, owing to the 80 unstable mounting of the pedestal 6 and the absence of any counterweight, lateral oscillatory movements will be imparted to the basket. These lateral movements will tend 85 to retard the centrifugal force and assist in the more even and gentle distribution of the metal within the mould, thus avoiding damage to the walls of the same.

90 In Fig. 4 the crucible is shown over the pattern with the connecting sprues between the sprue holes therein and the mould. It will be understood that the whole arrangement will have been properly invested with a suitable material, leaving only the opening in the crucible uncovered, before placing the investment in the basket 10, after which heat is applied below the basket and upon the metal within the crucible.

95 The preferred form of crucible used in the machine is illustrated in Fig. 3 and is according to United States Patent No. 1,534,952.

100 It contains a hearth on which the molten metal repose and in the hearth are preferably three small sprue holes over which the sprue pipe 14 is cemented. The crucible is 105 partially roofed in and on the edge of the partial roof near the opening is a down-

wardly depending flange 15. If the handle be turned in a direction to cause the investment basket to move towards the operator the molten metal will be forced up the side 5 of the crucible against the roof and the depending flange and will by the latter be deflected downwards over the sprues.

It is very important that the handle be turned in the right direction while the 10 molten metal is in the crucible otherwise it will be spilled and to avoid this happening, a means is provided for stopping the handle being reversed. This consists of a slotted plate 17 on one end of which is a hinged stop 15 member 18. This slotted plate is placed over and secured to a stud on the gear box 7, of which there may be several as desired, with the stop 18 near the handle that is thus prevented by the stop from being turned in the 20 wrong direction. When however the handle is turned correctly, it will after completing one revolution, come against the hinged member that will fall over and then lie flat on the plate 17. This is the preferred form 25 of stop recommended for use in this machine.

The spindle 9 is kept loose in its bearing to assist in promoting instability in the machine but instead of the spindle being of 30 lesser diameter than its bearing and parallel therewith it may taper therein, being of maximum diameter at its inner end. At its outer end the basket sleeve mounting is secured to the spindle which will be disposed 35 to knock about in its bearing when the uncounterweighted basket is rotated, thereby assisting in attaining the object this invention has in view, namely, to impart to the investment while being swung the necessary 40 lateral oscillatory movements, as explained.

Having now described my invention what I claim as new and desire to secure by Letters Patent is:—

1. In a machine for casting dentures in metal, an unstable standard and means 45 thereon for rotating an investment containing a mold and molten metal, said means comprising a horizontal spindle on the standard and a rod on the spindle from which the investment is suspended and to 50 which it is rigidly attached.

2. In machines for casting dentures in metal, an unstable baseplate, a pedestal thereon, a gear box on the pedestal, a rotatable spindle extending laterally from the 55 box and an investment basket having no counterweight secured to and suspended from the rotatable spindle.

3. In machines for casting dentures in metal, a pedestal, a gear box thereon, a rotatable spindle extending laterally from the gear box, an investment basket having no counterweight secured to and suspended from the rotatable spindle, an unstable baseplate to the pedestal, bolts that retain the 60 baseplate in position and cushion springs on the bolts below the plate and on which it seats.

4. In machines for casting dentures in metal, an unstable baseplate, a pedestal 70 thereon, a gear box on the pedestal, a rotatable spindle made to a loose fit in its bearing extending laterally from the gear box and an investment basket having no counterweight secured to and suspended from the 75 rotatable spindle.

5. In machines for casting dentures in metal, an unstable baseplate, a pedestal thereon, a gear box on the pedestal, a rotatable spindle made to a loose fit in its bearing 80 extending laterally from the gear box and an uncounterweighted investment basket secured to and suspended from the rotatable spindle.

In testimony whereof I affix my signature.
FREDERICK WM. NUNN.
